(57) **CLAIM**

The ornamental design for a snap button, as shown and described.

DESCRIPTION

FIG. 1 is a front, right, and top perspective view of a male portion of a snap button, showing my design.

FIG. 2 is a rear, left, and bottom perspective view of FIG. 1.

FIG. 3 is a front elevation view of FIG. 1.

FIG. 4 is a rear elevation view of FIG. 1.

FIG. 5 is a left side elevation view of FIG. 1.

FIG. 6 is a right side elevation view of FIG. 1.

FIG. 7 is a front, right, and top perspective view of a female portion of the snap button, showing my design.

FIG. 8 is a rear, left, and bottom perspective view of FIG. 7.

FIG. 9 is a front elevation view of FIG. 7.

FIG. 10 is a rear elevation view of FIG. 7.

FIG. 11 is a left side elevation view of FIG. 7.

FIG. 12 is a right side elevation view of FIG. 7; and, FIG. 13 is a front, right, and top perspective view of the snap button, wherein the male portion and the female portion are assembled.

The broken lines shown in the drawings are included for the purpose of illustrating portions of the snap button that form no part of the claimed design.
